CLAIM

The ornamental design for a grip for a fishing reel handle, as shown and described.

DESCRIPTION

FIG. 1 is a perspective view of the present invention; FIG. 2 is a perspective view of the present invention of FIG. 1;

FIG. 3 is a side elevation of the invention of FIG. 1, the opposite side being identical in appearance; and, FIG. 4 is an end view of the invention of FIG. 1.

The broken lines depict environmental structure and are included for the purpose of illustration and form no part of the claimed design.
